UNITED STATES PATENT OFFICE.

BENJAMIN FLEIGEL, OF CHELSEA, MASSACHUSETTS, ASSIGNOR TO HIMSELF AND JOHN W. NUTTER, COPARTNERS DOING BUSINESS UNDER THE FIRM-NAME AND STYLE OF B. FLEIGEL & CO., OF CHELSEA, MASSACHUSETTS.

SEWING-MACHINE ATTACHMENT.

No. 878,718.

Specification of Letters Patent.

Patented Feb. 11, 1908.

Application filed July 11, 1907. Serial No. 383,182.

To all whom it may concern:

Be it known that I, BENJAMIN FLEIGEL, a citizen of the United States, and a resident of Chelsea, in the county of Suffolk and State of Massachusetts, have invented an Improvement in Sewing-Machine Attachments, of which the following description, in connection with the accompanying drawing, is a specification, like letters on the drawing 10 representing like parts.

This invention has for its object the production of a novel sewing machine attachment to be used in connection with sewing machines for guiding braid, tape, piping, 15 welt, etc.

In accordance with my invention the attachment is provided with a vertically adjustable tubular guide-way through which is led to the material the braid, tape, piping, 20 welt or cord to be stitched in place by the usual needle of the sewing machine to the work-support of which the attachment is secured.

In many classes of work done by a sewing 25 machine attachment it is most desirable to be enabled to insure that the work being stitched piece after piece be stitched at exactly the same distance and under the same conditions, and frequently work of one kind 30 has to be interrupted temporarily and work of another kind introduced, and when work is resumed, in attachments as ordinarily constructed, the attachment has to be readjusted with relation to the needle forming 35 part of the stitch-forming mechanism.

In the attachment to be hereinafter described the working parts may be removed easily and inserted quickly to resume work, and the working parts will occupy always exactly the same relation and yet I have made 40 provisions to vary the conditions of the work, as for instance, the exact relation of the acting edge of the attachment to the needle when exigencies of the work require.

Figure 1 in plan view shows part of the work-support or bed of an ordinary sewing machine, and part of a presser-foot with my attachment secured to said support, parts of the arms carrying the attachment being 45 shown in dotted line in their inoperative positions; Fig. 2 is a side elevation of the parts shown in Fig. 1, said figure showing fabric as in position to be stitched; Fig. 3 is a left 50

hand end view of the attachment; Fig. 4 a section in the dotted line x, Fig. 1; Fig. 5 illustrates the work removed from the attachment after having been run through the same, as represented in Figs. 1 and 2; Fig. 6 shows the work, Fig. 5, in section on the dotted line 5 but with the material closer 60 together; Fig. 7 shows my attachment adjusted to guide a so-called "California welt" in boot and shoe work; Fig. 8 shows the first stages of work that may be done with the parts adjusted as in Fig. 7, and Fig. 9 shows 65 the same opened up.

Referring to the drawing, A represents a base plate adapted to be fixed in one position on the work-support A^X of a sewing machine by set-screw A'. The block A at its outer 70 ends receives two stud screws B, C that serve as pivots for two arms B', C' shown by full lines in their operative positions, said arms, when the parts to be described and carried thereby are not in use being capable 75 of being turned into their inoperative positions 180°, as shown by dotted lines at the right hand end of Fig. 1, so that the parts carried by said arms may be removed entirely away from the usual presser-foot A⁴ 80 and leave the presser-foot free from any obstruction of the free movement of the material thereunder. This provision enables part of the work being done to be guided mechanically and then the parts so 85 guiding the work to be turned readily aside, leaving the work to be manipulated and guided by hand, and then when the guided work is to be resumed, the parts of the attachment put temporarily into their inoperative 90 positions may be brought back into their operative positions and lie just the same with relation to the work under all conditions, so that the fabric stitched may all be stitched just alike.

The arm B' is held in its operative position by a spring catch r, attached to the block A and engaging a recess in the underside of the arm B', and a stud s passes through the block A into contact with the spring catch 100 r, so that when the stud is pressed down the catch is released. (See Fig. 4). The arm C' is held in its operative position by the feed of the material, which tends to hold this arm up against the block A.

Each arm B', C', as shown, is bored for a

part of its length to receive the shank, as *b*, *c* of attachment-carrying parts, the shank *b*, as I have chosen to illustrate the same being provided at its outer end with an edge gage *b'*, while the shank *c* is provided with an adjustable guideway *c'* for a braid, tape, piping, welt or cord *e*. The shank *c* is surrounded by a collar 2 made adjustable thereon and held in position by a set-screw 3 contacting with the shank. These collars are adjusted on the shank in accordance with the particular stitching to be done, and each shank inserted in the hole in its arm *B'* or *C'* may be held in its adjusted position by a suitable set-screw 4 or 5.

Now when it is desired temporarily to discontinue the use of the attachment-carrying parts represented in the drawing, the set-screws 4 and 5 may be removed and the shanks with their adjusted collars be withdrawn from the arms *B'*, *C'* and the same may be done absolutely without any vibration. Whenever the shanks of the attachment-carriers are again inserted in the arms *B'*, *C'* to be held therein by their set-screws 4, 5 the right hand ends of the collars abut the ends of the arms and constitute positioning devices.

It is obvious that should it be desired that the guideway *c'* occupy a different position, the collar 2 on the shank *c* may be adjusted thereon and again locked. The attachment parts to be described carried by the shanks *b*, *c* may be also put into their operative positions without removing the shanks from the arms *B'*, *C'* by simply turning said arms for 180° about their stud-screws *B*, *C*.

The shank *c* has at its outer end an upright flange or head *c*² provided with screw threads into which enter the threaded shank of screws *c*³ that are extended through slots *c*⁴ in a flange *c*⁵ of a plate *c*⁶ carrying the guideway or portion *c'* through which is led the tape, cord, or welt, the slots in said flange being of such length and width with relation to the diameter of said screws as to permit the plate and its guideway to be adjusted both vertically and horizontally on said head; vertically to accommodate for the thickness of fabric *h* to be moved between the under side of said plate and the work-support, it being understood that the plate is raised as the thickness of the material *h* increases, and vice versa; horizontally to enable the adjustment of the guideway toward and from the needle. The size of the slots in the flange being of both greater length and width than the diameter of the screws passing through them and being arranged parallel to each other also permits of an angular adjustment of the flanged plate on the head. In this way the guideway may be tipped to secure an easier introduction of the work, the end toward the needle being tipped down and that away from the needle being tipped up.

The shank *b* having at its outer end the edge gage *b'* enters a hole in the arm *B'* and is there held by the set-screw 4 and said shank is surrounded, in addition to the collar referred to, by a sleeve that may be adjusted thereon and held in adjusted position by a set-screw 9 surrounded by a block 10 bored for the reception of the shank 12 of an auxiliary presser-foot *f* that may be held in its operative or inoperative positions by a set-screw 14. The block 8 is held in its adjusted position on the screw 9 by a set-screw 15. The drawing in Figs. 1, 2 and 3 shows the auxiliary presser-foot in its operative position. The auxiliary presser-foot is put into its inoperative or retracted position by loosening the set-screw 14 and sliding the auxiliary dresser-foot shank 12 to the right, and may be held in its inoperative position by tightening the set-screw 14.

The drawing shows at *A*⁴ part of the usual presser-foot of the sewing machine under which the material being stitched is fed by the usual feeding device of the sewing machine. The usual needle of the stitch-forming mechanism penetrates the material at 16.

Figs. 1 to 3 show the attachment set for guiding material *h*, *h'* to have stitched therebetween by a line of stitches 17 the braid, tape, piping or welt *e* represented in Figs. 1, 5 and 6, as when making a lap-seam. After the two layers and the braid have been stitched, as shown in Figs. 1 and 2, the work is removed and the layer *h'* is turned over to the right, see Fig. 5, and thereafter another line of stitches 18 may be inserted parallel to the line of stitching 17, thus completing a lap-seam, and leaving the edge of the braid, tape or piping exposed, as in Figs. 5 and 6. When stitching, as shown in Figs. 1 and 2, one layer passes under the plate *c*⁶ the braid or tape, through the guideway *c'* and the other layer of material rests on the top of the guideway and on the under layer, and passes under the presser-foot.

Fig. 7 shows the attachment adjusted for putting a welt, commonly referred to in shoe making as a California welt, in the seam closing the quarters of a shoe, the same surrounding the heel and center.

Fig. 8 shows two pieces of leather *m* supposed to be parts of the quarters or heel covering portions of a shoe, and *n* represents the California welt to be stitched therebetween.

Fig. 9 shows the material of Fig. 8 opened out, as it will be in the shoe, leaving the edge of the welt *n* exposed vertically at the heel end of the shoe. To do this work the set-screw 3, holding the collar 2 on the shank *b*, will be loosened and the shank will be pushed to the left to place the face of the edge gage *b'* in such position with relation to the delivery end of the guideway *c'* that the right hand edge of the California welt leaving said

guideway will contact directly with the face of the edge gage and in vertical line with the edges of the two layers m, m of the material constituting the quarters of the shoe.

5 It will be obvious from the foregoing description that the attachment herein shown may be employed for a variety of work, and that the shanks shown may have connected with their heads any usual device commonly 10 employed in sewing machines for manipulating, guiding or turning work or fabric on its way to the needle to be stitched.

Having fully described my invention, what I claim as new and desire to secure by 15 Letters Patent is:—

1. In a sewing machine attachment, an arm, a carrier having its shank longitudinally and slidably mounted on said arm, an attachment mounted at the end of said carrier, a 20 positioning device applied to said shank loosely, means to secure said positioning device on said shank in any adjusted position, and means to secure said shank detachably in said arm with the positioning device 25 against said arm whereby the adjusted position of the attachment may be maintained during the removal from and replacement of the carrier in the arm.

2. In a sewing machine attachment, an 30 arm, an attachment carrier having its shank slidably connected with said arm and having a head, a plate flanged and provided with parallel vertical slots in said flange at one end to contact with said head and having at 35 its other end a guideway, combined with means to connect said flange and head whereby said plate may be adjusted vertically and at various inclinations on said head.

3. In a sewing machine attachment, an 40 arm, an attachment carrier having a shank slidably connected with said arm and provided with an edge gage, combined with a sleeve applied to said shank, a set screw to secure said sleeve on said shank, a block, an 45 auxiliary presser foot having its shank slidably mounted on said block and means to hold the shank of said foot in any position in

which it may be adjusted, said foot being adapted to be put in position to act on the material close to the face of said edge gage 50 or to be turned into its inoperative position.

4. In a sewing machine attachment, an arm, an edge gage sustained thereby, a second arm, an attachment carrier having its shank detachably sustained thereby, a 55 plate adjustably connected with and sustained by said attachment carrier and provided with a guideway, the plate and its guideway being adjustable vertically to accommodate for the thickness of the material 60 passing under said plate.

5. In a sewing machine attachment, a block, two arms, means to pivot both said arms on said block, means to retain said arms in their operative position, said arms 65 being free to be turned for 180° about their pivots, attachment carriers having their shanks slidably connected with both said arms, each carrier having a collar, means to secure the collars in adjusted position on said 70 shanks, means to connect said shanks to said arms, means to present a braid, piping, welt or cord to the material to be stitched, and an edge gage.

6. In a sewing machine attachment, a 75 block, two arms, means to pivot both said arms on said block, means to retain said arms in their operative position, said arms being free to be turned for 180° about their pivots, attachment carriers having their 80 shanks slidably connected with both said arms, each carrier having a collar, means to secure the carriers in adjusted position on said shanks, means to connect said shanks to said arms, means to present a braid, piping, 85 welt or cord to the material to be stitched, an edge gage, and an auxiliary presser foot.

In testimony whereof I have signed my name to this specification, in the presence of two subscribing witnesses.

BENJAMIN FLEIGEL.
